UNITED STATES PATENT OFFICE.

CHARLES W. SCHUBERT, OF CLEVELAND, OHIO.

DESIGNING OR CALCULATING CHART.

1,141,837.

Specification of Letters Patent. Patented June 1, 1915.

Application filed May 19, 1914. Serial No. 839,536.

To all whom it may concern:

Be it known that I, CHARLES W. SCHUBERT, citizen of the United States, residing at Cleveland, in the county of Cuyahoga and State of Ohio, have invented certain new and useful Improvements in Designing or Calculating Charts, of which the following is a specification.

This invention relates to designing or calculating charts for solving formulas, any or all letters of which may represent variables and part of which may represent constants. These charts are especially adapted for the use of designers, architects, engineers and others, and have for their object, to provide a simple and efficient chart which will save time in selecting or designing, either singly, or in combination, structural beams of any material, such as iron or steel beams, wooden beams of any practical dimensions, reinforced concrete beams, slabs and T-beams.

The charts comprise or include a series of five parallel lines, or axes, along part or all of which are plotted various logarithmic 25 graduations; other axes or lines may be used to further the purpose of the chart. The relations to which the logarithmic graduations are plotted along the five axes or lines have a constant ratio to each other, and 30 said relations form a part of this invention together with the ratio of the distances between the five lines of the above parallel series. There may or may not be associated with this series of parallel lines, a plurality 35 of notations, delineations, or representations, such as beams of various shapes, sizes, and materials, properly positioned with relation to the lines or axes along which the logarithmic graduations may or may not be plotted, 40 the arrangement being such that solutions may be indicated by means of an alinement either by a straight edge applied to the chart or by any other means, as a string or thread stretched across the chart alining the 45 variables as directed by keys or as directed in the text or by means of a straight line scribed on some transparent material, and the said material adjusted to the chart to aline the variables as indicated in the text, 50 or by keys of explanation on the chart.

By means of the chart, the required designations and sizes of beams or the like can be determined by inspection, by the use of the keys or as directed in the text.

The charts may be printed or otherwise 55 marked on sheets of any suitable material as paper, celluloid, etc.

Figure 1 is a plan of one of the charts. Figs. 2, 3, 4 and 5 are plans illustrating 60 various solutions on modified charts.

The lines indicating the five axes or the series of five parallel lines are indicated at 6, 7, 8, 9, and 10, the axis 11 in Figs. 3 and 5 and axis 12 in Fig. 5 being added to further the purpose of the charts, for illustration 65 as indicated by the solved formulas 17 in Fig. 3, and 18 and 49 in Fig. 5.

The five axes 6, 7, 8, 9, and 10 are spaced apart in the following described and indicated relations, namely: axis 9 is midway 70 between axes 6 and 10 as indicated by line 19, axis 7 is midway between axes 6 and 9 as indicated by line 20, and axes 8 is one-third ($\frac{1}{3}$) of the distance between axes 6 and 9 or 9 and 10 from the axis 9 as indicated by line 75 21. The above distances are to be measured on lines 19, 20 and 21 perpendicular to the above series of parallel axes as indicated by 22.

The ratio of the relation to which the 80 logarithmic graduations are plotted on the five axes are as described and indicated as follows:—On axes 6 and 10 the logarithmic graduations are plotted to a relation of one (1) as indicated at 23; on axis 9 to one-half ($\frac{1}{2}$) as indicated at 24; on axis 8 to one-third ($\frac{1}{3}$) as indicated at 25; on axis 7 to one-fourth ($\frac{1}{4}$) as at 26; such that the ratio of the plotting on axes 6 and 10 is the same or is one (1); on axis 6 or 10 to 9 is two (2); 85 and on axis 6 or 10 to 8 is three (3) and on axis 6 or 10 to 7 is four (4). Hence the relation of the logarithmic plotting on axis 6 or 10 is four (4) times that on axis 7; three (3) times that on axis 8; and two (2) times that 90 on axis 9, as indicated between the graduations six and ten or any decimal part or times six and ten, as sixty and one hundred, etc., as shown on chart in Fig. 2 or as indicated between the graduations one hundred 100 and two hundred, or any decimal part or times of said number written along the 105 graduations the same as shown on the chart in Fig. 3, thus ten to twenty; one thousand to two thousand. The above relation of plotting holds between any logarithmic plottings on said five axes.

The relative positions of the above men-

tioned logarithmic plottings on the series of parallel lines or axes are such as to solve the formulas as indicated on the keys or in the text by the alignment of the variables as indicated by the keys or as directed in the text. To further the purpose of the charts other logarithmic graduations besides the ones above referred to and related as above described may be plotted along the axes for example; as indicated along the axis 9 by 15 in Fig. 5 and along the axis 6 by 16 in Fig. 5.

In the general formula

$$15 \quad \phi = \frac{\rho \phi \omega \beta}{T}$$

when

$$\phi = M_b; \rho = 1; \phi = W; \omega = L; \beta = 1 \text{ and } T = 8$$

20 then we get

$$M_b = \frac{WL}{8};$$

further when $\phi = w_1$ and $\beta = 2$ we get

$$25 \quad M_b = \frac{w_1 L^2}{8};$$

as indicated at 14; also by similar substitutions of constants for the variables, etc., in 30 the general formula we get

$$M_b = \frac{12WL}{Y} \text{ or } \frac{12w_1 L^2}{Y}$$

and

$$35 \quad M_b = \frac{WL}{Y} \text{ or } \frac{w_1 L^2}{Y}$$

as indicated at 17; and $M_b = WL$ or $w_1 L^2$ as indicated at 13; and $W = w_1 L$ or $w_1 L^2$ as at 14; and $w_1 = wC$ as at 27. Other formulas are solved as indicated in Figs. 4 and 5, part of which are to be used in direct conjunction with those above given.

45 In applying the above formulas part of the variables are assumed and the other obtained as directed by the chart. For example:—To apply formula 14,

$$50 \quad \frac{WL}{8} = M_b$$

assume any two letters and read the value of the third; thus assume $M_b = 40,000$ ft. pounds and $L = 16$, then by aligning with line 28, 40 on axis 10 with 16 on axis 6 we read 55 $W = 20,000$ lbs. Total uniform load on axis 9; further we can read on axis 8, $w_1 = 1250$ pounds per lineal foot on beam, and then to solve $w_1 = wC$ we assume either C or w 60 and read the other. Say assume $w = 140$ lbs. per sq. ft. floor, then we read C on axis 6 as 8.75 ft. spacing by extending line 29 through 1,250 on axis 8, and 140 on axis 7, to intersect axis 6 at 8.75 ft. In similar 65 manner handle formula 17 which however

has a variable denominator Y and hence use another axis 11 to get final result

$$M_b = \frac{WL}{Y}.$$

In applying formula 14 to solve for M_b on axis 10, the section modulus for steel beams required at 16,000 pounds per sq. inch fiber stress is given on left side of axis 10 to correspond to M_b on right side, then on perpendicular lines out from axis 10 are plotted various structural materials that will correspond with this section modulus if of rolled steel shapes, or to correspond to M_b , if of reinforced concrete as indicated at 29; or stamped metal joist can be plotted at their proper relation to the above axis and to correspond to the M_b given. This is indicated at 30. Further there is plotted other steel rolled girder beams 31, or I-beams 32, 85 or H sections as 33; or supplementary beams at 34; ship channels 35; special 18 inch channels as 36; H's at 37 or X-ties at 38. More standard shapes of channels and I-beams are plotted at 39 and 40, and angles 90 at 41; and also in Figs. 4 and 5 are written in their proper position with respect to M_b which is not plotted on axis 10, the various sizes of wood timber for different fiber stress 43, corresponding to the kind of timber, all 95 as indicated at 42 in said figures. It is then noted that many charts can be made for the many various products of different companies and by one stroke of the pencil the carrying capacity of said material could be 100 determined. Thus to get the total load a 12" x 31.5 lbs. standard I-beam would carry on a 12 ft. span; draw a horizontal line through 12" at 31.5# beam and from this intersection of axis 10 draw line 44 cutting 105 axis 9 at required load.

By means of formula 45 Fig. 4 and plot- 110 tings on axis 6 for various fiber stress of wood we can get the M_r —moment of resistance for any size stick timber of any kind of wood for any safety factor, since $M_r = M_b$ by connecting this M_b to any span, line 46 we can get the load the timber will carry; for example: Required the safe load or a 2" x 10" on 9 ft. span, use 1200 fiber stress. 115 Through $b = 2"$ on axis 7, and 10 = depth on axis 6, draw the line 47 to intersect axis 9 at 2, then $bd^2 = 200$, from $bd^2 = 200$ draw line 48 to 1200 on axis 6 this line intersects axis 10 at $M_r = 3,300$ (exact = 3,333) from this intersection draw line 46 through $L = 9$ on axis 6 it cuts axis $W = 3,000$ # nearly and is the total safe uniform load the timber will carry, the line 46 cuts the axis 8 at 300 nearly which is the load per lineal foot the beam will carry, or the load per square foot if they are placed one (1) foot centers.

Other examples or formulas may be solved by means of the axes and the keys given such as formula 18 Fig. 5, etc., which will sug- 130

gest themselves to engineers or others skilled in the use of such formulas.

What I claim as new is:

1. A chart of the kind described, comprising a series of parallel lines marked with graduations dividing the same, said lines being spaced apart distances related to each other and to the divisions of the graduations, and a plurality of indicia of structural elements beside said lines and related in position to the graduation.

2. A chart of the kind described, comprising a series of parallel lines or axes provided with graduations, and indicia of various structural elements respectively, the distance apart of the lines or axes, and the division of the graduations, and the location of the indicia of said elements, being all related to each other, and adapted for

the solution of formulas by a straight line 20 crossing the chart or axes.

3. A chart of the kind described, comprising a series of five parallel axes 6, 7, 8, 9, and 10 spaced apart as follows: axis 9 midway between axes 6 and 10, axis 7 midway 25 between axes 6 and 9, and axis 8 one-third of the distance between axes 6 and 9, from axis 9; and logarithmic graduations plotted along said axes as follows: on axes 6 and 10 to a relation of one, on axis 9 to one-half, so on axis 8 to one-third, and on axis 7 to one-fourth.

In testimony whereof, I do affix my signature in presence of two witnesses.

CHARLES W. SCHUBERT.
